United States Patent Office.

GEORG BERGNER, OF WASHINGTON, MISSOURI.

Letters Patent No. 79,191, dated June 23, 1868.

IMPROVEMENT IN SHEARS.

The Schedule referred to in these Letters Patent and making part of the same.

TO ALL WHOM IT MAY CONCERN:

Be it known that GEORG BERGNER, of Washington, in the county of Franklin, and State of Missouri, have invented a new and useful Improved Bolt and Spring for Shears, of which the following is a full, clear, and exact description, reference being had to the annexed drawing, making a part of this specification, in which—

Figure 1 represents a pair of shears having my invention.

Figure 2 represents a detached view of my invention.

Similar letters indicate like parts.

The object of the invention is to arrange a spring for opening shears in such a manner that it will be simple, durable, and not interfere with the hand when using the shears.

In shears, A, of any desired form, I make the bolt b, fig. 2, somewhat larger than usual, with a thread, c, on one end, and over the head, d, I place a broad cap, e, figs. 1 and 2, all, however, made in one piece. In the side of the bolt, near the end, is a slot, h, made to receive a corresponding stud in the under blade k of the shears. The bolt being in place, it is secured by an ordinary nut. Through an opening in the head d is passed a coil-spring, o, figs. 1 and 2, which is wound around the head, its other end being curved so as to rest against the shoulder n on the upper blade s of the shears when the same are opened. It is evident that as soon as the pressure used to bring the blades together is removed, the tension of the spring will cause them to open at once, the slot in the bolt and its stud preventing the bolt from turning. Of course this spring and bolt may be applied to other instruments than shears, in fact to all which have the scissors-movement; consequently I do not limit myself to this particular instrument in the use of my invention.

What I claim as my invention, and desire to secure by Letters Patent, is—

The slotted bolt b, with its cap e, spring o, and shoulder n, all in combination, when arranged in relation to each other and the blades of the shears, substantially as and for the purpose specified.
